UNITED STATES PATENT OFFICE

2,514,662

THREAD-CUTTING SEAM OPENER

Ray H. McMurray, Oakland, Calif.

Application October 15, 1945, Serial No. 622,319

4 Claims. (Cl. 164—17.5)

1

My present invention relates to a seam ripping device, and more particularly to an attachment for sewing machines by which the threads of a stitched seam may be exposed and progressively cut as material containing the seam is advanced under the presser foot of the sewing machine.

An object of my invention is to provide a device for ripping machine stitched seams in which the threads of a seam are exposed and cut in a new and novel manner.

Another object of the invention is to provide an attachment that may be applied to the operating head of a sewing machine and operated by the needle bar in conjunction with the presser foot and feed thereof to cut the threads of a machine stitched seam.

Another object of the invention is to provide a device, having a reciprocating knife, that may be conveniently mounted upon the presser foot supporting bar of a sewing machine and in which the knife carried thereby is driven with a reciprocating movement by an operating connection with the needle bar of the machine.

Another object of the invention is to provide a machine stitched seam opening attachment that may be mounted upon a sewing machine and driven by the needle bar thereof so as to cut the threads of a seam in timed relation with the advance of the seam carrying material under the presser foot of the machine.

A further object of the invention is to provide a novel arrangement of a reciprocating knife and a supporting means therefor having an anvil-like portion over which the seam may be guided and parted to expose the threads of the seam to the operation of the knife as the uncut seam is moved over the anvil-like portion of the blade supporting means.

Other objects and advantages of my invention will be in part evident to those skilled in the art, and in part pointed out hereinafter in the following description taken in connection with the accompanying drawing, wherein there is shown by way of illustration and not of limitation a preferred embodiment thereof.

In the drawing:

Figure 1 is a fragmentary end view of a sewing machine head of conventional construction showing a preferred form of my device mounted thereupon,

Figure 2 is a fragmentary sectional view of the device shown in Figure 1 taken along line 2—2 of Figure 1,

Figure 3 is a top view of the device shown in

2

Figure 1 with the presser foot and needle bars shown in section,

Figure 4 is a sectional view taken along line 4—4 of Figure 1, and

Figure 5 is an enlarged fragmentary sectional view taken along line 5—5 of Figure 4.

In Figure 1 of the drawing I have shown, for the purpose of illustrating my invention, a preferred embodiment thereof as applied to the 10 operating head of a conventional sewing machine, here designated by the numeral 10. The operating head 10 of the sewing machine is provided with a presser foot supporting bar 11 that carries a presser foot 12 at its lower end. The presser foot 12 extends over and is adapted to cooperate with a work feeding mechanism 13 which operates to advance the work to be sewed in the path of a threaded needle (not shown) that extends from the end of a needle bar 14. The feeding mechanism 13, as is well understood, comprises a series of toothed members that gyrate so as to advance the work over a supporting table or bed 15 upon which the head 10 of the sewing machine is mounted. Mounted upon the presser foot supporting bar 11 by a suitable clamp, as will hereinafter appear, there is a blade enclosing housing 16 in which there is mounted a stitch cutting blade 17. In this particular showing the blade 17 is mounted to move in a slightly inclined 15 guideway 18 formed in the housing 16 so that its cutting edge will be disposed at a slight overhanging angle with respect to a seam guiding horn or anvil 19 which projects from the bottom of the enclosing housing 16 toward the presser foot 12. The lower end of the housing 16 is also 20 here shown as having an outwardly flared bottom portion 20 which, in conjunction with the horn or anvil 19, will facilitate the spreading of a stitched seam over the cutting edge of the blade 17 so as to expose the stitching thereof to the cutting action of the blade 17 as the latter reciprocates. As a means for imparting a reciprocating movement from the needle bar 14 to the blade 17, there is a walking beam 21 which is here shown as pivoted, as at 22, upon the housing 16. In order to provide for a simple and 25 convenient mounting of the device upon a conventional sewing machine, the enclosing housing 16 is, as is shown in Figure 3 of the drawing, provided with a friction gripping clamp 23 that is adapted to be tightened upon the presser foot supporting bar 11 by a thumb screw 24, and the walking beam 21 is provided with forked ends 25 and 26 that are adapted to respectively engage with a pin 27 carried by the blade 17 and a thumb

screw accommodating boss 28 upon the needle bar 14 in which a thumb screw 29 is threaded for securing a needle upon the end of the needle bar 14.

In addition to the horn or anvil 19 the device, as shown in Figure 2 of the drawing, is also provided with a downwardly depending bracket 30 which supports downwardly depending fingers 31 and 32 that are held in spaced relation with the upper surface of the anvil or horn 19 so as to guide a seam to be ripped over the anvil or horn 19 as the stitched seam is advanced under the presser foot 12 by the action of the feeding mechanism 13.

It is believed that the operation of my device will be apparent from the above description. However, upon referring to Figure 4 of the drawing it will be seen that as the work, shown in dot and dash lines, is advanced over the anvil or horn 19, with the seam in alignment with the blade 17, the stitching of the seam will be parted so as to expose the threads thereof to the cutting action of the knife 17 as it is reciprocated by the operation of the needle bar 14. During this operation, as is more clearly shown in Figure 5 of the drawing, the free edges of the material at the seam will be folded back upon the anvil or horn 19 as the work is guided thereover by the fingers 31 and 32. Then, as the material, with the stitched seam, is advanced or drawn under the presser foot 12 and around the housing 16 by a slight pull on the part of the operator, the seam will open and the exposed stitches will be progressively cut by the reciprocating blade 17.

While I have, for the sake of clearness and in order to disclose the invention so that the same can be readily understood, described and illustrated a specific form and arrangement, it is to be understood that the invention is not limited to the specific form disclosed, but may be embodied in other forms that will suggest themselves to persons skilled in the art. It is believed that this invention is new and it is desired to claim it so that all such changes as come within the scope of the appended claims are to be considered as part of this invention.

Having thus described my invention, what I claim and desire to secure by Letters Patent is:

1. In a seam ripping attachment for a sewing machine, the combination of a rearwardly disposed blade guiding support adapted to be secured to the presser foot supporting bar of a sewing machine head, a blade mounted for reciprocating movement upon said guiding support, an anvil-like horn disposed in alignment with and at the lower end of said blade and extending toward the presser foot upon said presser foot supporting bar over which a seam to be ripped may be moved, guide fingers carried by said blade guiding support and cooperating with said anvil-like horn for guiding the seam toward said blade, and a driving connection between the needle bar of the sewing machine and said blade for imparting a reciprocating movement to said blade as the seam is advanced over said anvil-like horn and by the action of said presser foot.

2. In a seam thread cutting device for use with a conventional sewing machine, the combination

of a sewing machine presser foot supporting bar having a presser foot at the lower end thereof, a needle bar adjacent said presser foot supporting bar, a blade enclosing housing mounted behind said presser foot supporting bar, a work supporting horn projecting from said housing toward and terminating at the lower end of said presser foot supporting bar, a blade mounted for reciprocating movement within said enclosing housing and having its cutting edge exposed at a slight overhanging angle immediately behind said work supporting horn, a pivotal bearing carried by said housing, and a walking beam connected at one end to the needle bar of the sewing machine and at its other end to said blade, whereby said blade will be caused to reciprocate in timed relation with the movement of a seam to be ripped as the stitched seam is advanced under said presser foot and over said horn by the operation of the sewing machine.

3. In a seam opening device, the combination of a blade guiding means adapted to be suspended over a work table, a blade movably mounted upon said guiding means with its cutting edge extending vertically and disposed outwardly from one side of said guiding means, means for imparting an operating movement to said blade, a horn-like seam guiding anvil projected outwardly from said guiding means at the lower end of said cutting blade over which material carrying a seam may be moved, said horn-like seam guiding anvil having a flared shoulder portion at its inner end adjacent said blade over which the stitched seam may be spread as the material carrying the seam is moved over said horn toward the cutting edge of said blade, and a guide means disposed over the outer end of said anvil for engaging the seam carrying material as it is moved over said anvil to the flared portion thereof.

4. In a seam opening device, the combination of a blade guiding support adapted to be suspended over a work table, a movable blade mounted upon said support with its cutting edge exposed at one side thereof, means for imparting an operating movement to said blade, a horn-like anvil projecting horizontally from said support in alignment with the cutting edge of said blade and over which a stitched seam may be spread to present the threads of the seam to the cutting edge of said blade, and a pair of spaced guide members at the outer end of said horn-like anvil adapted and arranged to engage a seam carrying material at each side of the seam and align the seam with said blade as the material is moved along said anvil toward said blade.
